Plastics, Inc., Wilmington, Mass., a corporation of
Maryland

Filed June 29, 1967, Ser. No. 7,638

Term of patent 14 years

(Cl. D94—3)

FIG.1

FIG.2

FIG. 1 is a front view of the flexible drinking straw;
FIG. 2 is a top view thereof.

The rear and bottom views are the same as the respective front and top views thereof.

The characteristic feature of the flexible straw of this invention lies in the top knurled-like portion in combination with a flexible portion in a flexible drinking straw.

I claim:

The ornamental design for a flexible drinking straw, as shown and described.
